ADJUSTABLE RING BOOK

Henry T. Adams, Chicago, Ill.

Application December 14, 1932, Serial No. 647,262

6 Claims. (Cl. 129—24)

This invention relates to adjustable ring books, or holders, and the like.

One of the objects of the invention is to provide a loose-leaf ring mechanism of cheap and simple construction which enables perforated sheets to be readily inserted upon the rings and withdrawn therefrom; and a ring mechanism in which the ring members may be readily removed from or secured on the binding strip. Another object is to provide means for operating the rings of the binder simultaneously, and means which will at the same time enable the rings to be adjusted longitudinally of the binder strip. Other objects and advantages will appear as the specification proceeds.

The invention is fully described in the following specification, and shown in the accompanying drawing, in which:—

Figure 1 is an end view of a loose-leaf book equipped with binder mechanism embodying my invention;

Fig. 2 is a sectional view of the binder mechanism, removed from the book, the section being taken as indicated at line 2 of Fig. 8;

Fig. 3, a similar sectional view, the ring members being shown in open position;

Fig. 4, a detail perspective view of one of the ring members;

Fig. 5, a sectional view, the section being taken as indicated at line 5, of Fig. 3;

Fig. 6, a perspective view of the cover or spacer member employed in connection with the binder mechanism;

Fig. 7, a perspective view of the metal back strip to which the ring members may be secured; and

Fig. 8, a plan view of the ring members, showing the tips of the rings in engagement.

In the illustration given, the book cover A is shown provided at its rear side with a metal back strip 1, which may be secured thereto by any suitable means, such as rivets.

The back strip 1 may be formed of a single piece of sheet metal. The sides of back strip 1 are preferably turned inwardly to form spring walls or edges 2; and at its ends, the back strip is preferably provided with upwardly struck supports 3, which are provided with a guide slot or recess 4. The recesses 4, at the ends of the back strip are adapted to receive the ends of a rod 5, which is secured against lateral displacement by the side walls of recesses 4.

A pair of complementary ring members or sections 6 are suitably connected to the rod 5 so as to form, when in closed position, one continuous ring. Each of the complementary ring members 6

is provided with a plate member 7, which is equipped with rearwardly extending lugs or heels 8 adapted to engage the inturned edges 2 of the back strip 1. Plate member 7 is shown provided at its front end with hinge 9, which preferably comprises alternate downturned curved lugs 9^a and upturned lugs or half-rings 9^b. The hinged ring members are so constructed that when two complementary rings are placed together, the curved lugs meet to form one continuous cylindrical hinge through which rod 5 may be inserted to secure the two members in operative relation.

Any desired number of similar rings may be placed upon the rod 5 in this manner. With the ring members in open position, the rod is lowered into slot or recess 4, the backwardly extending heels 8 of plate 7 being inserted beneath the inturned edges 2.

Pressure upon rod 5, or the ends of rod 5, forces the plate members 7 downwardly until the ring members 6 assume the closed position, shown in Fig. 2. In this position, the plate members 7 slant downwardly from the heels 8 towards the hinge portions 9, and thus anchor the ring members rigidly against the inturned edges 2. The inturned edges or walls 2 serve as a spring to hold the plate member in the downwardly inclined position.

When rod 5 is raised, thus springing back the edges 2, the hinges 9 permit the plates 7 to assume the upwardly inclined position, shown in Fig. 3, and the ring members 6 are opened. The spring tension of the inturned edges 2, although less in this position, serves to hold the plates 7 in upwardly inclined position, and thereby holds complementary ring members 6 open.

It will be observed that when the ring members 6 are in closed position, the plate members 7 are almost at right angles to the side walls or inturned edges 2 of the plate 1, and therefore the plates at this point exert pressure against edges 2. On the other hand, when the complementary ring members 6 are in open position, the plate members 7 incline slightly upwardly so that very little pressure is exerted against the side walls or edges 2. When in open position, therefore, the ring members 6 may be adjusted longitudinally of the rod 5 with ease.

If desired, a spacer cover or retaining member 10 may be employed. Preferably this consists of a convex strip of material having lugs 11 at both of its ends which engage the inturned edges 2 of the back strip 1 so as to secure cover 10 thereto. Cover 10 may be provided at an intermediate point with lugs 12 which are centrally recessed to

receive a pair of complementary rings 6. With this type of cover, a pair of ring members may be retained by means of recessed lugs or guides 12 in a fixed position with respect to the cover 10 5 or back strip 1, while the remaining ring members may be adjusted along the spaces between lugs 12 and lugs 11. If desired, any number of spacing lugs 12 may be employed. Any suitable means, such as a threaded cap 13, engaging a threaded 10 15 end of the rod 5 may be employed to secure rod 5 against longitudinal displacement.

The side walls of ring members 6 are preferably curved rearwardly so as to form members substantially semi-circular in cross section. Rings 15 of this shape conform on the inner side to the shape of the holes in the sheets of paper.

It will be observed that with the ring construction illustrated, the entire mechanism is readily separable, the complementary ring members 6 20 being removable from rod 5 and the rings also being readily removable from back plate 1. The desired number of rings may be quickly placed upon rod 5 and adjusted to a position which will enable them to receive previously perforated parts 25 of paper. In case of injury to one of the complementary ring members, the defective part may be removed and replaced with a new part. The mechanism is simple, sturdy and may be constructed at very little cost.

30 As shown more clearly in Fig. 8, the tips of the rings each have a saw-tooth shape which permits the rings to be used interchangeably on opposite sides of the pivot rod 5.

The foregoing detailed description has been 35 given for clearness of understanding only, and no unnecessary limitations should be understood therefrom, but the appended claims should be construed as broadly as permissible, in view of the prior art.

40 I claim:

1. In a ring book, a metal back strip provided with spring side walls having inturned edges which are uniformly straight throughout their length, separable ring sections shiftable longitudinally of said back strip, each of said ring 45 sections having a curved portion and angularly disposed heels extending from said curved portion and engaging a side wall so as to support said curved portion away from said inturned edge, and a cover member having lateral extensions received under the inturned edges of said side walls, said lateral extensions being spaced apart longitudinally so as to provide longitudinal slots between said edges and said cover through 50 which said ring sections may be shifted.

55 2. In a ring book, a metal back strip provided with spring side walls having inturned edges, at

least one pair of complementary and interchangeable ring sections shiftable longitudinally of said back strip and equipped with interlocking hinge elements, a pivot rod engaging said hinge elements, each of the ring sections having a curved portion and an angularly disposed projection extending from said curved portion and engaging a side wall of the back strip so as to support said curved portion away from its corresponding inturned edge, and a cover member having lateral extensions received under the inturned edges of the side walls, said lateral extensions being spaced apart and affording longitudinal slots between said edges and said cover through which said ring sections may be shifted. 80 85 90

3. In a ring book, a metal back strip provided with spring side walls having inturned edges, a pair of ring sections slidably secured to said back strip, and a cover member having lateral extensions received under the inturned edges of said side walls, said lateral extensions being spaced apart and affording longitudinal slots between said edges and said cover through which said ring sections may be shifted. 95

4. In a ring book, a metal back strip provided with spring side walls having inturned edges, a plurality of pairs of ring sections slidably secured to said back strip, and a cover member having lateral extensions received under the inturned edges of said side walls, some of said lateral extensions being spaced apart and affording longitudinal slots between said edges and said cover through which some of said ring sections may be shifted, and at least two of said lateral extensions being spaced close together so as to engage at least one of said ring sections to prevent the shifting thereof. 100 105 110

5. In a ring book, a metal back strip provided with spring side walls, a pair of ring sections slidably engaging said side walls and shiftable longitudinally of said back strip, and a cover member having lateral edge portions interlocked with said spring side walls, said cover member having portions cut away and affording longitudinal slots adjacent said spring side walls 115 120 through which said ring sections may be shifted.

6. In a ring book, a metal back strip provided with spring side walls, at least one pair of ring sections slidably engaging said side walls and shiftable longitudinally of said back strip, and a cover member having lateral edge portions interlocked with said spring side walls, said cover member having a closed central portion and having also lateral portions cut away and affording longitudinal slots adjacent said spring walls 125 130 through which said ring sections may be shifted.

HENRY T. ADAMS.
